UNITED STATES PATENT OFFICE.

CHARLES A. WENBORNE, OF CHICAGO, ILLINOIS, ASSIGNOR TO THE WENBORNE-KARPEN DRYER CO., A CORPORATION OF WEST VIRGINIA.

DRYING APPARATUS.

1,087,563.

Specification of Letters Patent.

Patented Feb. 17, 1914.

Application filed March 29, 1911. Serial No. 617,784.

To all whom it may concern:

Be it known that I, CHARLES A. WENBORNE, a citizen of the United States of America, and a resident of Chicago, county 5 of Cook, State of Illinois, have invented certain new and useful Improvements in Drying Apparatus, of which the following is a specification.

The main object of this invention is to 10 provide an improved form of drying apparatus of general utility and particularly adapted for drying veneered stock, furniture and other materials or articles having glued joints.

15 A specific embodiment of this invention is illustrated in the accompanying drawing, which represents a transverse section of a drying room designed for the drying of glued materials.

20 In the form shown in the drawing, the drying room is a rectangular structure with well insulated walls and ceiling. About fifteen-sixteenths of the cubic space therein forms the dry room proper. It reaches from 25 end wall to end wall, and transversely from one side wall 1 to a vertical partition 2 located near the opposite side wall 3 and arranged to provide a narrow air duct 4, which is coextensive with the drying room 5, and 30 communicates therewith both above and below the partition 2. The upper and lower openings 6 and 7 are also co-extensive with the length of the room.

A heating coil 8 extends horizontally 35 across the drying room and the pipes thereof are uniformly distributed over the horizontal area of the room so that the heating effect will be uniform. This coil is supported by transverse beams 9, preferably 40 pipes. Above the coil 8 and spaced away from it is a slotted floor 10, which supports the material to be dried. This floor is preferably built up of slats placed on edge, being spaced apart by suitable spacer blocks 11 45 and fastened together by means of tie rods 12 extending through the spacer blocks 11.

Below the coil 8 and spaced above the floor 13, at a distance substantially equal to the distance of the partition 2 from the wall 3, 50 is a screen or partition 14 which is so formed as to permit a free and uniformly distributed flow of air through it at all points of its horizontal area, but is so arranged that the air passages are tortuous to such an extent that no heat rays can pass directly from the heating coil through the screen 14 into

the space 15 below it. To this end, the screen 14 is in the form shown built up of a series of parallel slats of V-shaped cross-section, spaced apart equally, but nested one 60 within the next in such manner that a straight line cannot be drawn through the air passages without intersecting one of the slats.

The partition 2 and screen 14 divide the 65 whole space into a rectangular drying chamber and an L-shaped air duct which has a vertical leg 4 and a horizontal leg 15 respectively coextensive with the vertical and horizontal areas of the drying chamber 16. 70 The partition 2 is air-tight and well insulated, and is jogged toward the drying chamber 16 at its upper part to provide a shelf 17 above which is mounted a condenser 18 comprising a series of coils, 75 through which water may be circulated. Below the condenser 18 is a drip pan 19, which is inclined toward the air duct 4 and has at its lower edge a trough 20. This trough is inclined lengthwise of the drying 80 room so that the water collected by it will be discharged through a suitable outlet pipe at the end of the kiln. Depending from the ceiling 21 in approximate alinement with the partition 2, is a baffle wall 22, which extends downward to about the level of the upper row of coils of the condenser and thus insures that all of the air flowing over the top of the partition 2 must pass into 85 contact with the condenser in its passage to 90 the air duct 4.

The condenser has the effect of cooling the air and reducing its ability to hold moisture. The excess of moisture is condensed upon the pipes of the condenser and is finally collected by the drip pan and directed into the trough 20, which conducts it to the outside. The cooled air in the vertical leg 4 of the air duct is heavier per unit of horizontal area than the heated air in the dry- 100 ing chamber 16. This causes a downward air current in the duct 4 and an upward air current in the drying chamber 16. The cooled air passes down through the duct 4, through the opening 7, and then flows along 105 the floor, filling the duct 15 with air of uniform temperature and pressure throughout the horizontal area of that duct. The heating coil 8 heats the air uniformly throughout the entire area of the coil and the tendency of the air to flow upward is equal at 110 all points. This equal flow is insured by the

2

screen 14, which prevents the heat radiated from the heating coils from entering the horizontal leg 15 of the air duct, and thereby insures that the air in said horizontal leg will be influenced only by the tendency of the air above to rise after being heated. This feature, perhaps more than any other, has made it possible to produce the uniformity of treatment which is essential to success in the rapid drying of glued material. In prior constructions, where the radiation from the heating coils toward the floor of the kiln has not been completely intercepted, the floor becomes heated and the cold air coming in contact with it is thereby prematurely heated and caused to rise instead of distributing itself over the entire area of the floor. This gives rise to an unequal air current, that is, the upward current is stronger adjacent to the inlet opening than at a distance from said opening, and results in such irregularity in the drying action as to render such prior constructions impractical for drying glued joints. I am aware that attempts have been made to correct this by the insertion of diaphragms and deflecting plates, but as far as I am aware, this fault has never been successfully corrected prior to the erection of kilns of my invention.

Although but one specific embodiment of this invention is herein shown and described, it will be understood that numerous details of the construction shown may be

altered or omitted without departing from the spirit of this invention, as defined by the following claim:—

I claim:—

A drying apparatus, comprising a drying chamber, an air duct having one end communicating with the upper part of said chamber and the other end communicating with the lower part of said chamber, heating means extending across the chamber above and near the lower end of the duct and having a multiplicity of air passages extending upwardly through the same and distributed throughout its area, a screen extending across the chamber above the point of communication between said chamber and the duct and below said heating means, and having a multiplicity of tortuous air passages extending upwardly through the same and distributed throughout its area, said screen being adapted to prevent direct radiation of heat from said heating means into the part of the chamber below said screen, and thereby prevent heating of the floor and consequent precipitant rising of the air a support for the material to be treated located above said heating means, and a condenser located in said air-duct.

Signed at Chicago this 25th day of March 1911.

CHARLES A. WENBORNE.
